UNITED STATES PATENT OFFICE.

GEORGE E. MIRFIELD, OF YOUNGSTOWN, OHIO, ASSIGNOR TO THE YOUNGSTOWN SHEET & TUBE COMPANY, OF YOUNGSTOWN, OHIO, A CORPORATION OF OHIO.

METHOD OF MANUFACTURING WELL POINTS.

Application filed January 2, 1925. Serial No. 230.

This invention has to do with improvements in well points and the method by which they are manufactured. The invention relates particularly to well points for driven wells, such, as are used in the draining of soil adjacent to foundations, but the invention is not limited to this class of service.

The main object of the invention is to provide a well point which is integral with a section of pipe, preferably perforated for the entrance of the drainage water.

Heretofore it has been customary to make the well point separate and distinct from the pipe section above them, the point being connected to the pipe section by riveting or otherwise. This type of construction is objectionable for various reasons including the fact that the point section itself must be shrouded to receive the end of the pipe section, besides which the cost of manufacture and number of manufacturing steps is considerably increased.

The main object of the present invention is to provide a well point section including not only the point itself, but also the pipe section adjacent thereto, all made as a unitary and integral element including not only the pointed end portion, but also the perforated pipe section for the drainage water. This will greatly increase the strength and durability of the structure, will improve its resistance to shock and damage during the process of sinking it into place, and at the same time provide a greatly improved article which is superior in many other ways as compared to a built up structure.

In connection with the above I have also devised a method of manufacture for producing the articles above referred to, which method includes various steps of a process which is so worked out that the plain pipe section can be very easily and effectively forged or otherwise worked into the desired pointed end product.

Other objects and uses of the invention will appear from a detailed description of the same, which consists in the features of construction and combinations of parts herein-after described and claimed.

In the drawings:

Figure 1 shows a longitudinal section through a portion of plain pipe in its original condition;

Fig. 2 shows the pipe section of Fig. 1 as

the same is held in suitable jaws while its end portion is swaged in order to increase the thickness of the metal therein;

Fig. 3 is a view similar to that of Fig. 2, with the exception that during the swaging operation the outside diameter of the pipe has also been materially increased;

Fig. 4 shows diagrammatically the next step of the process as compared to Fig. 2 (or Fig. 3) including the use of a suitable die for drawing together the extreme end portion of the metal and closing the same while at the same time increasing its thickness;

Fig. 5 shows a section through the point after the next step of the process, which consists in drawing down the point by the use of suitable dies which are illustrated diagrammatically in Fig. 6;

Fig. 6 shows a view looking into the dies used in the forming operation which results in Fig. 5.

Fig. 7 shows an outside view corresponding to Fig. 5;

Figs. 8 and 9 show cross sections on the lines 8-8 and 9-9, respectively, of Fig. 7, looking in the directions of the arrows; and

Fig. 10 shows a view similar to Fig. 7, with the exception that it illustrates a modified form of construction in which the upsetting operation is carried to such an extent as to establish a definite shoulder immediately behind the point, Fig. 10 illustrating the point which results from the type of upsetting operation illustrated in Fig. 8.

I first take a pipe section, preferably of more or less uniform diameter, as shown at 11 in Fig. 1. I next grip the same in suitable jaws 12 and 13 some distance behind the extreme end 14 of this pipe section, and then swage or otherwise upset said extreme end portion so as to reduce its length and simultaneously increase the thickness of the metal, as clearly illustrated in Fig. 2. Sometimes this operation is carried to the extent illustrated in Fig. 3 in which there is established a definite shoulder 15 close to the jaws 12 and 13.

This is, of course, accompanied by increasing the thickness of the metal in the end portion of the pipe section materially beyond that illustrated in Fig. 2. After bringing the end portion of the pipe section to the condition illustrated in either Fig. 2 or 3, the end portion is so treated as to bring it into a tapered condition, as illustrated in Fig. 4.

This will substantially close the extreme end of the opening of the pipe, as shown at 16, besides further increasing the thickness of the metal in the portion 17. This particular operation may be performed by the use of a die 18, such as illustrated in Fig. 4, having a tapered socket 19. The die may be worked back and forth a number of times commencing with the pipe in the condition illustrated in Fig. 2 or 3, and terminating with the condition illustrated in Fig. 4.

After the end portion of the pipe has reached the condition of Fig. 4, this end portion is drawn out into a somewhat more tapered condition, as illustrated in Fig. 5. This will not only produce more of a taper in the end portion of the section, but will carry some of the stock beyond the position of the closure 16 so as to establish a solid point 12. The amount of metal in this point, will, of course, depend upon the manner in which the operation is conducted as well as the angle of the point itself, but preferably a sufficient amount of metal stock should be carried into the point to give it the necessary strength and body to withstand the work it must perform as the well point is sunk.

In order to produce the point illustrated in Fig. 5 use may be made of a pair of companion female dies 21 and 22 which may be forced towards each other by a series of blows in order to gradually bring the stock into the desired condition. Preferably these dies are provided with companion hexagonal surfaces 23, so that a similar finish will be established on the metal of the well point. These hexagonal surfaces taper towards one end of the dies, as is clearly evident in Fig. 6, and preferably the dies terminate short of the full amount of the taper so as to leave an end opening 24 when the dies are fully closed. These dies may be worked along the metal of the well point as they are forced towards each other so as to gradually bring the entire point into the desired shape.

As illustrated in Figs. 5 and 7, the pipe section behind the point is provided with a series of perforations 25 through which the drainage water is received into the bore of the pipe. These perforations preferably commence at a point close behind the position of the tapered point itself.

When shaping up a section of the form illustrated in Fig. 3 into its final condition the shoulder 15 or a material portion thereof will be retained at the back end of the tapered point. As a consequence, the size of the point itself is somewhat larger than that of the pipe section proper and the opening formed in the ground as the point is forced down will be somewhat larger than the pipe. This will make it easier for the pipe to follow into the ground.

In practice it is preferred that after completing the operation illustrated in Fig. 4, the

end portion of the pipe section should be reheated prior to the forging operation, illustrated in Figs. 5 and 6. Furthermore, in some cases the use of the forging die, of the form illustrated in Fig. 4, may be eliminated 70 and the end portion of the pipe section, as illustrated in Fig. 2, may be reheated and directly subjected to the forging operation of Figs. 5 and 6. This is particularly true in the case of larger sizes. 75

It will also be noted that the operations above explained include an upsetting operation, as illustrated in Fig. 2 or Fig. 3, a closing operation, as illustrated in Fig. 4, and a drawing out operation, as illustrated in Figs. 80 5 and 6.

While I have herein shown and described only certain embodiments of the feature of my present invention, and also only certain steps of a process for practicing the invention, still it will be understood that I do not intend to limit myself to the same, except as I may do so in the claims. 85

I claim:

1. The process for the manufacture of a 90 well point which consists in first backwardly swaging the end portion of a uniform cylindrical tube to reduce its length and simultaneously increase the thickness of its metal, thereafter reducing the size of said end portion and tapering the same and substantially closing the passage therethrough, thereafter reheating the end portion, and thereafter forging the reheated end portion to elongate the same into the form of a solid tip and establish the desired exterior taper substantially as described. 95

2. The process for the manufacture of a well point which consists in first backwardly swaging the end portion of a uniform cylindrical tube to reduce its length and simultaneously increase the thickness of its metal, and establish an exterior rearwardly facing shoulder at the back side of the swaged end portion, thereafter forcing the swaged end portion longitudinally into the tapered socket of a female die for the purpose of further reducing the size of said end portion and tapering the same and substantially closing the passage therethrough, thereafter reheating the end portion, and thereafter forging the reheated end portion to elongate the same into the form of a solid tip and establish the desired exterior taper, substantially as described. 100

3. The process for the manufacture of a well point which consists in first backwardly swaging the end portion of a uniform cylindrical tube to reduce its length and simultaneously increase the thickness of its metal, 110 thereafter forcing the swaged end portion longitudinally into the tapered socket of a female die for the purpose of further reducing the size of said end portion and tapering the same and substantially closing the pas- 115

- sage therethrough, and thereafter forging the reheated end portion to elongate the same into the form of a solid tip and establish the desired exterior taper, substantially as described.
4. The process for the manufacture of a well point which consists in first backwardly swaging the end portion of a uniform cylindrical tube to reduce its length and simultaneously progressively increase the thickness of the metal toward the end thereof, thereafter progressively reducing the exterior cross dimensions of said end portion, and tapering the same to bring the thickened terminal portion into closed relation, thereafter reheating the end portion, and thereafter forging the reheated end portion to elongate the same and taper out the same into a solid tip portion merging backwardly into conically extending walls of diminishing thickness to the line of mergence with the tube, and to give to the exterior of the point a tapering polygonal formation, substantially as described.
- 10 5. The process for the manufacture of a well point which consists in first backwardly swaging the end portion of a uniform cylindrical tube to reduce its length and simultaneously progressively increase the thickness of the metal toward the end thereof, thereafter progressively reducing the exterior cross dimensions of said end portion, and tapering the same to bring the thickened terminal portion into closed relation, thereafter reheating the end portion, and thereafter forging the reheated end portion to elongate the same and externally taper out the same into a solid tip portion merging backwardly into conically extending walls of diminishing thickness to the line of mergence with the tube, substantially as described.
- 15 6. The process of manufacturing well points comprising swaging the end portion of a cylindrical tube to reduce its length and simultaneously increasing the thickness of its metal, and thereafter forging the said thickened end portion to a closed point.
- 20 7. The process of manufacturing well points comprising swaging the end portion of a cylindrical tube to reduce its length and simultaneously increase the thickness of its metal substantially uniformly throughout said end portion, and thereafter forging said thickened end portion from the thickened inner end to the outer edge to a closed point to gradually increase the thickness of metal towards the closed point.

GEORGE E. MIRFIELD.
